Heinrich Kern

UNITED STATES PATENT OFFICE

HEINRICH KERN, OF TELLNITZ, CZECHOSLOVAKIA

AEROPLANE WITH VERTICALLY OSCILLATABLE WINGS

Application filed June 27, 1931, Serial No. 547,311, and in Czechoslovakia June 5, 1929.

This invention relates to an aeroplane with wings oscillatable up and down, which are hinged to short supporting planes and automatically driven from the propeller shaft by suitable transmissions and driving means, the oscillatable wings themselves having apertures automatically opening and closing like Venetian blinds.

An embodiment of the invention is illustrated by way of example in the accompanying drawings in which:

Fig. 1 is a vertical longitudinal section through the supporting planes and the right oscillatable wing.

Fig. 2 is a top plan view of Fig. 1, partly in section.

Fig. 3 is a vertical part section through one of the wings on a slightly larger scale.

In the hull 1 the engine 2 with cooler 3 is built in the usual manner. The shaft 5 carrying the propeller 4 is arranged in known manner inclined at an angle to the longitudinal axis of the hull and the rotating movement of the shaft 5 transmitted by a worm 6 and a worm wheel 6a to a shaft 7, which acts on two shafts 9 through the intermediary of clutches and pairs of bevel wheels 8. On the outer ends of the shafts 9 crank discs or cranks 10 are mounted, the free ends of which engage the axles 13, which are connected by struts 12 and 12a to wings 14 and consequently effect the raising and lowering of the wings.

The bevel wheels 8 and shafts 9 are arranged under the supporting planes 15, which in the example illustrated are rigidly connected to the hull. The supporting planes are preferably hollow and taper towards the end, to which the wings 14 are movably connected by means of pins 14a.

The upper surface of the oscillatable wings is provided with a staying and in the practical construction the wings are made of hard wood plates connected like plywood. Apertures 14b in the oscillatable wings are automatically closed by flaps 16 during the downward movement of the wings, and these flaps open during the upward movement of the wings. The movement of the flaps is limited in the open position by stops 17. The

oscillatable wings in their lowest position, as long as the aeroplane runs on the ground, are situated with their ends slightly above the surface of the ground, as can be seen from the position of the right wing shown in dot-dash lines in Fig. 1. The aeroplane rests with its sprung carriage, carrying the hull 1, on runner wheels 18.

The supporting surfaces 15 need not be rigidly connected to the hull as illustrated in the above example, but they may be oscillatable around the axis of the worm wheel 6.

An indicator may be fitted on the dash board in front of the pilot's seat designed to show the actual position of the slowly ascending and descending wings, so that the driver is in a position to stop the engine so that the oscillatable wings remain adjusted in a position best suited for gliding.

I claim:

1. An aeroplane, comprising in combination short supporting planes, oscillatable wings adapted to move up and down on said supporting planes, cranks adapted to effect the up and down movements of said oscillatable wings, crank shafts adapted to actuate said cranks, connecting rods connecting said shafts to said cranks, an intermediate shaft adapted to drive said crank shafts, bevel wheels adapted to transmit the movement of said intermediate shaft to said crank shafts, a propeller wheel, a worm, and a worm wheel adapted to transmit the rotary movement of said propeller shaft to said intermediate shaft.

2. An aeroplane as specified in claim 1, comprising in combination with the oscillatable wings having apertures, flaps adapted during the upward and downward movements of said wings to automatically open and close said apertures in the wings like Venetian blinds, and stops adapted to limit the lifting movement of said flaps.

In testimony whereof I affix my signature.

HEINRICH KERN.
